UNITED STATES PATENT OFFICE.

EMIL WEBER AND FRANK C. FREY, OF BAKER CITY, OREGON.

BOTTLE-CLOSURE AND BRUSH.

SPECIFICATION forming part of Letters Patent No. 722,170, dated March 3, 1903.

Application filed June 15, 1901. Renewed June 12, 1902. Serial No. 111,392. (No model.)

To all whom it may concern:

Be it known that we, EMIL WEBER and FRANK C. FREY, citizens of the United States, residing at and whose post-office address is 5 1933 Court street, Baker City, in the county of Baker and State of Oregon, have invented new and useful Improvements in Bottle-Closures and Brushes, of which the following is a specification.

10 This invention relates to a mucilage-bottle closure and brush, and the primary object thereof is to provide a combined closure and brush which will effectually seal the bottle, making the same practically air-tight and yet 15 be adapted to be readily removed.

A further object is to provide means for adjustably securing the closure to the brush-handle to provide for the varying depths of the brush owing to the amount of mucilage 20 in the receptacle.

The peculiar construction of the device, as well as the manner of using the same, will be clearly described hereinafter and the novel arrangement of parts clearly disclosed in the 25 accompanying drawings, in which—

Figure 1 is a side elevation of a brush and closure constructed in accordance with our invention, and Fig. 2 is a vertical longitudinal sectional view through the same.

30 Referring now to the drawings by numerals of reference, 1 designates an expandible frusto-conical tubular handle comprising a sheet of spring metal wound in upwardly-tapering spiral form with overlapping edges 2 and 3, and in the lower extremity of the handle we provide a brush 4. Sleeved on the handle is a stopper 5, of cork or other suitable resilient material. 6 designates a casing surrounding the closure 5 and having an overlapping annular flange 7, which is adapted to 35 rest upon the edge of the bottle-neck. The casing 6 is preferably composed of a composition of lead and tin. The purpose of this combination of metals is to prevent adhesion 40 to the bottle.

Slidably secured within the tube 1 is a longitudinally-extending rod 8, carrying on its lower end a ball 9, the other end of the rod being bent at right angles to form a handle 45

10, whereby the ball may be drawn toward the 50 reduced end of the handle and thereby expand the same so as to fit tightly against the inner walls of the cork or closure 5.

In actual practice the cork or closure 5 will normally be in engagement with the handle 55 at a point adjacent the brush. As the contents of the bottle are used it will be necessary to adjust the stopper toward the upper extremity of the handle, so as to admit of the immersion of the brush, and in order to securely fasten said stopper to the handle the ball is drawn up through the medium of the rod, thus expanding the tube and forcing it tightly against the inner walls of said stopper. This will securely fasten the cork in its pre- 60 determined adjustment and it may be successively adjusted as occasion arises. When it is desirable to change the device to another bottle to reduce the distance between the brush and the stopper, it will only be necessary to force the ball downward toward the greater diameter of the handle, which will permit the stopper to be readily positioned at any convenient point thereon. By reason of the fact that the handle is made of spring 70 metal, as soon as tension is removed therefrom it will readily resume its normal shape.

While we have described and illustrated the preferred form of this device, we are aware that slight changes and alterations may be 80 made from time to time without affecting the merits of the invention, and we therefore reserve the right to make such changes and alterations as would properly come within the scope of the invention without departing from 85 the spirit thereof.

Having thus fully described the invention, what is claimed as new, and desired to be secured by Letters Patent, is—

1. In a device of the character described, 90 the combination with a tubular and expandible brush-handle, of a closure sleeved thereon, and means for expanding the handle so as to hold the closure at any predetermined point.

2. In a device of the character described, 95 the combination with a frusto-conical, tubular handle made from a sheet of spring metal

and provided with overlapping edges, of a closure sleeved on said handle, and means for expanding the handle from the interior so as to secure the closure at any convenient point thereon.

3. In a device of the character described, the combination with an expansible, tubular brush-handle, a rod longitudinally movable therein, means on the end of said rod for expanding the handle, of a closure carried thereby consisting of resilient material and provided with an outer metallic casing, said

closure being adapted to be adjustably secured at any convenient point on the handle.

In testimony whereof we affix our signatures in presence of witnesses.

EMIL WEBER.

FRANK C. FREY.
